UNITED STATES PATENT OFFICE.

WILHELM WILLENBÜCHER, OF MANCHESTER, ENGLAND.

TROLLEY-HEAD FOR ELECTRIC TRAM-CARS.

SPECIFICATION forming part of Letters Patent No. 772,638, dated October 18, 1904.

Application filed January 7, 1904. Serial No. 188,048. (No model.)

To all whom it may concern:

Be it known that I, WILHELM WILLENBÜCHER, a subject of the King of Prussia, Emperor of Germany, and a resident of Manchester, in the county of Lancaster, England, have invented a new and useful Improvement in Trolley-Heads for Electric Tram-Cars, of which the following is a specification.

This invention relates to trolley-heads for electric tram-cars in which the grooved trolley-wheel, together with a fork or the like which facilitates its emplacement on the conducting-wire, is capable of swinging around a vertical pivot.

15 The primary object of the invention is to effect the raising of the fork into the operative position by means of the cable usually attached to the trolley-pole without throwing the strain on the wheel-bearings when lowering the trolley-head.

For the purpose of my invention I attach the cable to the forward end of the fork and pass it through a hole in the upper part of the wheel-bracket adjacent to the vertical 25 wheel-pivot, and thence diagonally through the bracket over a small roller or pin on the trolley-socket. In the cable I arrange within the trolley-bracket a disk or similar stop, which after a limited downward pull of the 30 cable sufficient to raise the fork into its operative position comes in contact with the trolley-head socket, and the lowering of the trolley-head is then effected without throwing any strain on the trolley-wheel bearings. The 35 fork may be maintained in or returned to its inoperative horizontal position by gravity. Preferably, however, I arrange between the disk on the cord and the trolley-head socket a coiled spring on the cable, or otherwise so 40 arrange or dispose a spring which has the tendency to support the cable and allow the fork to assume its horizontal position. As this spring offers a certain resistance to the downward motion of the cable, the pressure 45 between the trolley wheel and conductor may be eased by lightly pulling the cable when passing points or sharp curves, while the fork remains in its horizontal position.

In order that my invention may be better 50 understood, I will more fully describe it with

reference to the accompanying drawings, in which—

Figure 1 shows a side elevation of the improved trolley-head with the fork in its operative position; Fig. 2, an end elevation of 55 the same; and Fig. 3, a modification of the improved trolley-head, in which the cable is in the customary manner attached to the trolley-pole and the fork shown in its horizontal position is raised by a separate cord connected 60 with the cable. The fork is in this modification shown pivoted to the bearing of the trolley-wheel spindle.

The trolley-wheel *a*, together with the fork *b*, which facilitates its engagement with the 65 trolley wire or conductor *c*, is adapted to swing around a vertical pivot in the bearing *d* on bracket *n* upon the trolley-head-socket *e*, attached to the pole *f*. The forward movement of the fork *b*, the prongs of which are 70 connected together at their forward ends by a cross-bar *b'*, is limited by the stops *r* on the bearings of the trolley-wheel spindle.

In Figs. 1 and 2 the cable *g* for lowering the trolley-head is attached to the forward 75 end *b'* of the fork, the prongs of which are pivoted on the trolley-wheel axis, and is passed through a hole in the upper rib of the bracket *n* and thence diagonally across the bracket to a pin *p* on the socket *e*, from which it hangs 80 down. On the cable within the bracket *n* a disk *h* or similar stop is provided which, after a limited downward pull of the cable during 85 which the fork is raised, comes in contact with the trolley-head socket when the lowering of the trolley-head commences. Preferably, however, I arrange between the disk *h* and the socket *e* a coiled spring on the cable, as shown in the drawings, which has the 90 tendency to maintain the fork in its inoperative position and which offers a certain resistance to the downward motion of the cord, so that the trolley-head may be eased by lightly pulling the cable when passing points or sharp curves while the fork remains in its 95 inoperative position.

In Fig. 3 the cable *g* for lowering the trolley-head is attached to the pole *f*, and a separate cord *g'* is used for working the fork in the same manner and by the means described 100

with reference to Figs. 1 and 2. The fork is in this modification shown pivoted to the bearings of the trolley-wheel spindle.

What I claim is—

- 5 1. The combination with a trolley-pole, of a bracket fixed on the end of said pole, a grooved trolley - wheel capable of angular motion around a vertical pivot and adapted to engage the conducting-wire, a fork the outwardly-extending prongs of which lie on either side of the wheel being pivoted intermediate their ends on the trolley-wheel axis and connected together at their forward ends and means for raising the fork by the cable for lowering the 15 trolley-head without throwing any strain on the trolley-wheel bearings when lowering the trolley-head, substantially as described.
2. The combination with a trolley-pole, of a bracket fixed on the end of said pole, a grooved 20 trolley-wheel capable of angular motion and adapted to engage the conducting-wire, a fork the outwardly-extending prongs of which lie on either side of the wheel being pivoted intermediate their ends and connected together 25 at their forward ends, a cable attached to the said closed end of the fork and passed through the upper rib of the bracket and over a pin on the socket, and a stop arranged on the cable within the bracket and adapted to come 30 in contact with the trolley-socket subsequent to the raising of the fork which is adapted to return to its inoperative position by gravity, substantially as described.
3. The combination with a trolley-pole, of a 35 bracket fixed on the end of said pole, a grooved trolley - wheel capable of angular motion around a vertical pivot and adapted to engage the conducting-wire, a fork the outwardly-extending prongs of which lie on either side of the wheel being pivoted intermediate their ends on the trolley-wheel axis and connected together at their forward ends by a cross-bar, a cable attached to the said cross-bar and passed 40 through a hole in the upper rib of the bracket and adjacent to the vertical wheel-pivot and thence diagonally across the bracket over a pin on the socket, and a stop arranged on the cable within the bracket and adapted to come 45 in contact with the trolley-socket subsequent to the raising of the fork which is adapted to return to its inoperative position by gravity, substantially as described.

to the raising of the fork which is adapted to 50 return to its inoperative position by gravity, substantially as described.

4. The combination with a trolley-pole, of a bracket fixed on the end of said pole, a grooved trolley - wheel capable of angular motion 55 around a vertical pivot and adapted to engage the conducting-wire, a fork the outwardly-extending prongs of which lie on either side of the wheel being pivoted intermediate their ends on the trolley-wheel axis and connected 60 together at their forward ends by a cross-bar, a cable attached to the said cross-bar and passed through a hole in the upper rib of the bracket and adjacent to the vertical wheel-pivot and thence diagonally across the bracket over a 65 pin in the socket, a spring and a stop arranged on the cable within the bracket and adapted to compress said spring which has the tendency to support the cable and allow the fork to assume its inoperative position, substantially 70 as described.

5. The combination with a trolley-pole, of a bracket fixed on the end of said pole, a grooved trolley - wheel capable of angular motion 75 around a vertical pivot and adapted to engage the conducting-wire, a fork the outwardly-extending prongs of which lie on either side of the wheel being pivoted intermediate their ends on suitable bearings and connected together at their forward ends by a cross-bar, 80 a cord attached to the said cross-bar and passed through a hole in the upper rib of the bracket and adjacent to the vertical wheel-pivot and thence diagonally across the bracket over a pin on the socket, a spring, a stop arranged on the 85 cord within the bracket and adapted to compress said spring which has the tendency to support the cable and allow the fork to assume its inoperative position, and a cable attached to the trolley-pole and connected with 90 the other end of the cord, substantially as described.

In testimony whereof I affix my signature in presence of two witnesses.

WILHELM WILLENBÜCHER.
